TELEVISOR TRANSMISSION SYSTEM

Waldemar Ilberg, Berlin, Germany, assignor to
Telefunken Gesellschaft für Drahtlose Tele-
graphie m. b. H., Berlin, Germany, a corpora-
tion of Germany

Application December 6, 1930, Serial No. 500,467
In Germany December 11, 1929

10 Claims. (Cl. 178—7.5)

The present invention relates to television systems and particularly to television systems wherein the Braun tube constitutes the medium by which the received picture is rebuilt. The suggestion has repeatedly been made in the prior art to utilize a Braun cathode-ray tube for the recreation or recording of the picture at the receiving end of a televiser transmission system. Such systems have been proposed by Dieckmann and Glage, Rosing, Schmiesser, and others.

With such a system a sharply concentrated or focussed cathode-ray pencil is caused to impinge upon a fluorescent screen, and this pencil, by suitable electrostatic or electromagnetic deflecting means, is directed successively along definite paths corresponding to the sequence of scanning or exploration of the picture elements at the sending end over the picture field. So long as a mere black-white contrast picture transmission without half-tones is dealt with, intensity control of the constituent picture units or elements may be insured in this scheme by always switching the current feeding the cathode-ray pencil in or out completely at the correct instant by control actions sent out from the televiser transmitter equipment.

However, if an attempt is made to thus obtain transmission or reproduction of half-tones as is mostly imperative in practical television transmission, the above arrangement fails to operate satisfactorily. The underlying cause is that quantitative alterations of the feed current of a Braun tube which might be insured by an amplifier inserted in the circuit will invariably result also in a changing potential fall across the discharge gap and thus varying velocities of the cathode-ray particles or electron stream. This, in turn, precludes regular distribution of the picture points since the size of deflections caused in the electrons by the electrostatic or electromagnetic field depends upon the speed thereof, so that intensity control and coordinate control are interdependent.

This difficulty is to be avoided according to the present invention by the principle hereinafter to be disclosed in that recourse is had to time modulation rather than amplitude modulation. For this purpose the method of operation is to be such that the Braun tube is traversed by current of a very definite strength which is always completely switched in and off without intermediate values of the current being allowed to flow during appreciable time intervals. Inside a picture unit or element the relationship between the time of connection or flow and the duration of current disconnection is to be so chosen that the integral effect upon the eye, inside this picture element, will correspond to its brightness. Hence, the rate of switching of the current must be chosen so high that no spatial dissolution or

discontinuity is occasioned owing to the coordinate motion of the fluorescent spot. In other words, the switching frequency or rate should be at least as high as, or, better still, higher than, the maximum still analyzable frequency of the picture impulses.

The accompanying drawing illustrates the principles of operation of the invention, wherein Fig. 1 illustrates the production of five different brightness values; Fig. 2 illustrates one suitable form of transmitter equipment for carrying out the time-modulation principle; and, Fig. 3 shows a suitable form of receiving equipment.

To produce the current impulses corresponding in length to the brightness of the picture elements scanned at the sending end, such as shown by Fig. 1, there is used a glow-discharge lamp receiving its working current from a battery by way of a photo-electric cell 2, the latter being influenced by the brightness of the original copy. As the photoelectric cell 2 is illuminated, intermittent discharges are set up in the glow-discharge gap in well-known manner, and the time sequence or time interval thereof, that is, the time sequence of the discharges, is approximately proportional to the luminous intensities striking the photo-electric cell 2. A variable condenser 3 connected in parallel relation to the glow-discharge gap allows of suitable adjustment of the frequency of these discharges. By amplifier means 4 and 5 the current impulses arising inside said gap are amplified and radiated off by the transmitter 6 in the form of picture impulses.

The receiver, apart from a demodulator and amplifier 7 is conveniently equipped with suitable limiting means or a manipulator device 8 adapted to restore all incoming picture impulses or signals to the same potential amplitude in spite of such fading effects as may have acted thereon over the air route in radio transmission, restoration to like potential values being imperative for the use of the modulation principle here disclosed. The manipulator 8, as is well known from the prior art, may, for instance, comprise a wave generator the oscillations of which are released locally by such incoming impulses as exceed a certain minimum threshold value. These oscillations are rectified and thus converted into direct current impulses as far as feasible of rectangular shape, and these rectangular direct current impulses in turn feed the discharge gap of the Braun tube 10 either directly or else by way of a direct current amplifier stage 9. The Braun tube receiver 10 comprises the usual cathode 11 and anode 12 and a tubular member 13 for concentrating the electron stream 14 which is directed toward the fluorescent screen 15. For controlling the cathode ray stream 14 the usual horizontal and vertical deflecting plates 16 and 17 are pro-

vided. Each of these sets of plates may be connected in any desired manner to a synchronizing source so as to produce a movement of the cathode ray pencil 14 which will correspond in position to the position of each elemental area of the transmitter as scanned.

If necessary, a residual current may be allowed during the dark periods provided they do not occasion an appreciable brightening of the fluorescent screen.

Having now described my invention, what I claim and desire to secure by Letters Patent is the following:

1. In a television receiving system wherein a cathode ray tube is used as the electro-optical image reconstructing device, the method of reproduction which comprises receiving, rectifying and amplifying television signals, limiting the amplitude of all of the signals to a constant value to produce time modulated representations of the received signals, and interrupting by the time modulated representations the cathode ray stream generated within the tube so as to produce the effect of intensity variations of the resultant image in accordance with the presence or absence of the cathode ray stream impinging upon the tube observation screen.

2. In an electro-optical image reproducing system, means for receiving, rectifying and amplifying signals, means for producing time modulated representations from the received signals comprising means for limiting the amplitude of the signals to a single predetermined value, a cathode ray tube for electro-optically converting the signals into visible representations, and means for impressing the amplitude limited time modulated signals upon the control circuit of the cathode ray tube to produce electro-optical representations during the presence of signals and to prevent electro-optical representations during the absence of signals.

3. In a cathode ray television system, the method of reception which comprises receiving and rectifying incoming signalling impulses corresponding to television image signals, limiting all rectified signalling impulses to equal amplitude, developing an electron ray, controlling the continuity or interruption of the developed ray by the rectified and limited signals, and controlling the position of the observable effect produced by the cathode ray stream as controlled and interrupted by the signalling impulses.

4. In a cathode ray television system, the method of reception which comprises receiving and rectifying incoming signalling impulses corresponding to television image signals, limiting all rectified signalling impulses to equal amplitude, developing an electron ray, controlling the continuity or interruption of the developed ray by the rectified and limited signals, and controlling the position of the observable effect produced by the signal from the controlled cathode ray stream.

5. The method of controlling observable effects in a cathode ray device which comprises generating a cathode ray stream, projecting the generated stream toward a fluorescent window to produce thereon an observable effect, deflecting the cathode ray stream along a plurality of paths bearing an angular relationship to each other to control the position of the observable effect produced, and producing an intensity control of the observable effect by interrupting the projected cathode ray streams for time intervals varying in

proportion to the intensity of the observable effect which is to be represented.

6. The method of controlling observable effects in a cathode ray device which comprises generating a cathode ray stream, projecting the generated stream toward a fluorescent window to produce thereon an observable effect, deflecting the cathode ray stream along a plurality of paths bearing an angular relationship to each other to control the position of the observable effect produced, and producing an intensity control of the observable effect by periodically interrupting the cathode ray stream in its passage toward the fluorescent window for time intervals of varying duration proportionate to varying intensities of light and shadow to be represented.

7. In an image reproducing device a cathode ray tube having a source of cathode rays and a screen upon which the cathode rays are adapted to impinge to produce observable effects, means cooperating therewith to deflect the developed cathode rays along a plurality of paths bearing an angular relationship with respect to each other so as to control the position of the observable effects produced, means for receiving signals of which an electro-optical indication is desired, means for limiting the amplitude of all of the received signals to a single predetermined value, and means for applying the amplitude limited signals to pass and interrupt the developed cathode ray in its passage between the source and the screen in accordance with the presence or absence of voltage output from said limiting means.

8. In a cathode ray device, a source of cathode rays, a screen upon which said cathode rays are adapted to produce observable effects, means for deflecting the cathode rays along a plurality of paths bearing an angular relationship with respect to each other to control the position of the observable effect produced upon the screen, an electrode interposed between said source of cathode rays and said screen, means for converting received signals into constant amplitude time modulated signals, and means for supplying to the said electrode said time modulated signal potentials appearing in the output circuit of said converting means so as either to block periodically the ray in its passage to the screen or to permit the ray developed to pass to the screen.

9. A system for producing images having the effect of varying intensity throughout which comprises a cathode ray device having therein a source for producing cathode rays and a screen upon which said cathode rays produce observable images, means for causing the cathode ray to sweep across the screen at a predetermined rate, and means for passing or interrupting the cathode ray in its path toward said screen with a time rate of passage or interruption of the stream proportionate to the intensity which is to be observed upon the screen.

10. A system for producing images having the effect of varying intensity throughout which comprises a cathode ray device having therein a source for producing cathode rays and a screen upon which said cathode rays produce observable images, means for causing the cathode ray to sweep across the screen at a predetermined rate, and means for interrupting the cathode ray in its path toward said screen at a time rate proportionate to the varying intensities of light and shadow to be imaged upon the screen.
